(57) **CLAIM**

I claim the ornamental design for a perfume bottle, as shown and described.

DESCRIPTION

FIG. 1 is a front elevational view for a perfume bottle showing my new design, the rear elevational view being identical;

FIG. 2 is a left side elevational view thereof, the right side elevational view being identical;

FIG. 3 is a top plan view thereof; and,

FIG. 4 is a top, front, left perspective view thereof.
